OIL-FIRED FURNACE

John W. Westwick, Galena, Ill.

Application March 16, 1938, Serial No. 196,241

9 Claims. (Cl. 126—116)

My invention relates to furnaces and heaters, particularly warm-air furnaces such as used for heating residences and the like. My furnace is especially designed for use with an automatic burner in which oil or other fluid is employed as a fuel.

The warm-air furnace which I have invented embodies a main structure that is of a built-up character; i. e., it is made of a plurality of side-by-side sectional units that may be bolted together to provide a complete body. In this manner, the size of the furnace may be readily enlarged or reduced according to the requirements of a particular installation. Since each section or unit is secured to an adjacent section, it is possible for the entire series of sections to expand or contract uniformly without opening the joints between them. The sections have an oval outline on their exterior walls and have central areas that communicate entirely through the body for the passage of the air that is being heated for circulation, and the sides of sections, alongside the central areas are tubular and are provided with inwardly inclined external fins to direct a proportion of the circulating air against the hot surfaces of the sections and into the central areas. At the bottoms of the sections there are spaces extending the width of the furnace below and communicating with the tubular sides, and these spaces combine to provide a compartment in which the combustion or fire-chamber is disposed. The fire-chamber is a casting of a somewhat ovoid shape and it is vented on its sides at or near its bottom segment in order that the hot gases from the oil-burner nozzle will be retarded and will be compelled to travel towards the outside of the furnace body when leaving the chamber to produce a maximum distribution of heat on the walls of the furnace body. The dimensions and shapes of the lower spaces of the sections relative to the dimensions and shape of the ovoid combustion chamber permits the latter to be readily inserted or removed horizontally through the front of the furnace body whenever desired. A casing or housing of any suitable shape surrounds the furnace body and the latter is supported in a framework above the floor so that the air being heated may circulate below the body and rise upon both sides thereof. I have provided means within the furnace body which tend to retard the speed of travel of the hot gases and to retain them within the body for a comparatively long period of time before they are discharged into the stack and in this manner the walls of the furnace body

are maintained at a high temperature with the consumption of a small amount of fuel. My experiments have shown that furnaces constructed on the principles herein disclosed may be successfully and efficiently operated with materially less fuel than can other types of furnaces at present available.

The arrangement of the component parts of my furnace is quite compact so that it occupies a relatively small area, and it is capable of being quickly erected at the place of installation. In its performance my furnace is efficient and effects a considerable saving in fuel consumption, and it is sturdily built in order to withstand severe usage. Furthermore, it is economical to manufacture and may therefore be sold at a reasonable retail price.

Other objects and advantages of my furnace will be apparent to persons skilled in the art after the construction and operation thereof is understood. I prefer to practice my invention substantially in the manner herein explained, the accompanying drawings being referred to for a better understanding of the characteristics and use of my invention. These drawings, while more or less schematic, disclose the principles of my warm-air furnace and a typical or preferred form in which the parts of my furnace may be made and assembled.

In the drawings:—

Figure 1 is a view in front elevation of my furnace, showing portions of an air-conditioner unit associated therewith, the front walls of the casing being removed.

Figure 2 is a top plan of the furnace with two of the sectional units broken away and in section.

Figure 3 is a vertical transverse section taken on line 3—3 in Figure 4 looking towards the front in the direction of the arrows.

Figure 4 is a vertical longitudinal section taken on line 4—4 in Figure 1 looking in the direction of the arrows.

Figure 5 is a view showing one of the sectional units of the furnace detached and in perspective.

Figure 6 is a side elevation of the furnace body removed from the casing.

The casing shown in the drawings is of the cubical type having a front wall 5, side-walls 6 and 7, and a rear-wall 8, and there is a top or cover 9 that supports a plenum chamber 10 from which the distributing ducts or conduits 11 extend. At the lower portion of side-wall 7 there is an elongated opening 12 that communicates with the discharge side of a suitable air-impeller 55

or fan 13 in an air-conditioner cabinet 14 on the side of the shell. Air filters 15 are disposed above the fan, and the return air, entering the cabinet through the return-air pipe 16, passes through the filters, (as well as such other instrumentalities required for air-conditioning) before being discharged into the furnace shell for heating the same. Supplemental walls 17 are mounted in spaced relation on certain of the walls of the shell for the purpose of heat insulation. At the front of the shell, and extending beyond the front wall 5 thereof, there is a vestibule 18 that encloses an oil-burner unit 19 that is supported above the floor on a suitable standard 20 (Fig. 4) and has its flame nozzle 21 passed through the front of the casing and furnace body so that it discharges into the fire-chamber.

The furnace is supported above the floor within the casing by a skeleton framework consisting of a plurality of posts 22 having their upper ends connected by horizontal saddles 23 in which the bottom portions of the sectional units of the furnace are seated. There is a comparatively large opening in the lower portion of the front wall 5 of the casing which opening is surrounded by a recessed bezel 24 of irregular or Z-shape in cross-section and the inner flange of this bezel is secured to the adjacent furnace section by bolts 25. The oil-burner nozzle has a flange 26 about midway its length that is bolted to a closure plate 27 of a shape and size to seat in the recess of the bezel 24 so that it may be secured in position upon the extended shanks of the bolts 25 that mount the bezel. The central portion of closure plate 27 is provided with an opening for the nozzle 21 and this opening is surrounded by a tapered stub 28 that projects inwardly a short distance to abut the face of the front wall of the fire chamber as shown in Figure 4. By means of the arrangement just described the burner 19 with the closure plate 27 provide a structure which may be readily attached to the bezel 24 as a unit or demounted therefrom by removing the nuts on the outer ends of the bolts 25.

The shape and size of the fire chamber 29 permits of its insertion or removal through bezel 24 surrounding the front opening. The fire chamber is made in two complementary hollow castings or shells 30 that are disposed with their edges abutting and connected together by bolts or screws that pass through aligned ears 31 on the outer surfaces of the shells. The front wall of the chamber has an opening 32 into which the burner nozzle 21 is inserted and said wall is provided with a peep-hole 33 above the opening to permit observation of the flame through an inspection aperture 34 in the closure front plate 27. The aperture 34 is preferably covered by a piece of heat-resisting glass or other suitable material for protection and for preventing escape of hot gases. Horizontally elongated egress openings 35 are made in the lower portions of the side walls of the fire-chamber which permit escape of the hot gases and flames out of the chamber and into the section furnace body for circulation in the latter, and, as seen in Figure 4, these egress openings are below the plane of the burner nozzle, which permits the chamber to become filled with the flames and said flames must travel downward to escape from the chamber. The inner surface of the chamber is lined or coated with a substantial layer of refractory material 36 which is applied thereto in a plastic state prior to assembling the half-sections of the fire-chamber

castings. It is understood the fire-chamber is assembled in a unitary form before being inserted into the sectional body.

This furnace body, as hereinbefore mentioned, is a composite structure that is built-up from a plurality of sections which are assembled side-by-side in order that a body of any desired size may be readily obtained. These sections or units are each in the form of an integral casting made from the same mold or pattern which effects considerable economy of manufacture. In Figure 5 I have shown one of these sectional units in perspective to more definitely bring out certain details thereof. The sectional unit comprises tubular side members 37 which are spaced apart to provide a central area 38 between their inner facing portions. As shown in section in Figure 2, the vertical tubular members 37 are somewhat oval in shape. Their upper portions merge into a barrel-shaped member 39 that has a horizontal axis and is hollow so that the members 37 discharge into it. The length of the barrel-shaped member 39 is greater than the horizontal width of the upper portions of the tubular members 37 so that short collars 40 are provided outside the tubes 37 at each end of the barrel-shaped member 39. Suitable lugs 41 are formed on the collars 40 to receive bolts in order to assemble adjacent units to each other. Below the central area 38 the tubular side members curve inward towards each other to provide a lower chamber 42 having relatively wide arched openings 43 that are surrounded by substantially L-shaped flanges 44 which are provided with lugs to receive other bolts for securing the sectional units together. The lateral faces of the L-shape flanges 44 of one section are disposed against the corresponding portions of an adjacent section and, as seen in Figure 6, the faces of flanges 44 and the outer ends of collars 40 and lugs 41 are all in one vertical plane that is parallel to the adjacent sides of the tubular members 37.

When several sectional units are assembled, the lower chambers of these units provide a continuous bottom passageway A extending longitudinally through the furnace body from end-to-end thereof and the barrel-shaped upper members 39, axially alining with each other provide an upper longitudinal passageway B also extending from end-to-end of the furnace body. The openings 43 in the lower portions of the sections provide communication between one section and the next section and are of sufficient dimensions to permit the fire-chamber unit to be inserted endwise into the same through the front of the furnace.

The flames or hot products of combustion, finding egress from the fire-chamber through the lower openings 35 therein, discharge into the lower passageway A and travel upwardly through the tubular members 37 and into the upper passageway B, transmitting the heat to the castings forming the sectional units, and are discharged from top of the rear section into a pipe 45 leading to the chimney or stack. In order to retard their movement, and hold back or retain the hot products of combustion within the furnace body, I place a baffle plate 46 at the junction between the last two sectional units of the furnace body so that the hot gases will travel downwardly in the sectional unit, designated as X in Figure 4, through the tubular members 37 and into the rear portion of the lower passageway A, preferably back of the fire-chamber 29. As a further hindrance to the movement of the hot gases, I

mount a baffle 47 at the juncture of the last two sectional units, the lower edge of which baffle terminates above the bottom of passageway A so that the hot gases must pass under the lower edge 5 of said baffle and then travel upwardly through the tubular members 37 of the rear unit and thence into the stack. For the purpose of balancing the stack temperature, and proportionating it to the temperature of the furnace body, there is a supplementary outlet 48 in the portion of the rear sectional unit near the upper portion of the passageway A and an elbow 49 extending from this opening 48 leads to a T-coupling 40 interposed in the pipe leading to the stack. The flow through 10 this elbow and supplementary outlet is controlled by damper 51 so that it may be shut off whenever desired.

The air which is returned to the furnace through the return-air conduit 16 discharges into 20 the bottom of the casing through the opening 12 and is of the forced-draft type due to the action of the blower or fan 13. This return-air enters the bottom of the casing and impinges upon the hot surfaces of the furnace body and circulates 25 around the same and between the tubular members 37 and passes out above the body into plenum chamber 10 for distribution. A certain proportion of the circulating air passes into the central areas 38 of the respective sections, which 30 areas combine to provide a longitudinal warm-air passageway C. In order to assist in directing the circulating air inwardly towards this passageway C and between the units, I have provided a plurality of inwardly and upwardly inclined fins 52 upon the lower portions of the exteriors of the tubular members 37 near their lower portions so that the air is directed between 35 said members and into the heating area C. In order to provide for a uniform heating of the 40 walls of the tubular members they are especially designed in the cross-sectional shape shown in Figure 2. Each tubular member embodies a plurality of walls a, b, and c, the wall a being outermost and disposed lateral to the other walls, and 45 the side walls b and c being converged towards each other in a general direction away from the lateral wall a. The tapered walls b and c provide a more constricted space between them that becomes gradually smaller towards their meeting 50 edges that are remote to the lateral wall so that the hot gases, traversing the interior of the tubular member in the direction of least resistance, will be urged away from the constricted space towards outer wider area near the wall a. In 55 this manner I secure more uniformly heated wall surfaces against which the air-currents being heated will impinge.

The shapes of the sectional units create a natural and unobstructed travel for the air-currents 60 being heated, and the disposition of the combustion passages and tubes results in a more uniform heating of the furnace body walls. I have also provided a radiating surface of increased dimensions resulting in maximum efficiency of the 65 furnace. It will be seen the fire-chamber may be readily removed endwise out of the furnace body for repair whenever desired; the oil-burner may be detached by itself as a unit; and the furnace body may be built-up into any number of required sections depending upon the service desired for a particular installation. The individual sections of the furnace body are bolted or otherwise secured to each other, and, on account 70 of their special shape, expansion of the metal 75 will not open any of the joints such as would

occur if all of the sections were held together by elongated tie-rods.

What I claim is:

1. A warm-air furnace embodying a casing; a furnace body housed in said casing, said body provided with horizontal upper and lower inner passages communicating with each other and adapted to be traversed by products of combustion, said body provided also with outer passages adapted to be traversed by air being heated; and a fire-chamber unit disposed in the lower horizontal inner passage, said unit embodying a hollow shell provided with means solely in its lower portion for egress of products of combustion therefrom into said lower horizontal 10 passage, said shell also provided with other means for discharging ignited fuel thereinto. 15

2. A warm-air furnace embodying a casing; sectional units therein, each said unit embodying an upper header, a lower header having sides 20 extending generally in a vertical direction, tubular columns communicating with said headers, the openings between said columns and said lower header being substantially the height of said vertical sides; the lower headers together 25 providing a horizontal heat passageway adjacent the bottom of said casing; and a fire-chamber unit in said heat passageway, said fire-chamber unit embodying a closed shell and provided with means in its lower portion adapted to discharge hot products of combustion into the lower portion of said heat passageway. 30

3. A warm-air furnace embodying a casing; sectional units therein, each said unit embodying an upper header, a lower header having a 35 rectangular shaped lower portion provided with substantially vertical side-walls, tubular columns connecting and communicating with said headers, the openings between said columns and said lower header extending from the top to the bottom of said header in said vertical side-walls; the said lower headers together providing a horizontal heat passageway adjacent the bottom of said casing; and a fire-chamber unit in said 40 heat passageway, said fire-chamber unit embodying a closed shell provided with elongated openings adjacent its bottom, whereby hot products of combustion from said fire-chamber unit are discharged opposite to and directly towards the openings into said columns. 45

4. A warm-air furnace embodying a casing; a furnace body housed in said casing, said body provided with horizontal upper and lower inner passages, means connecting and establishing communication between said passages, said passages and said means adapted to be traversed by products of combustion, said body provided also with outer passages adapted to be traversed by air being heated; and a fire-chamber unit disposed in said lower horizontal passage, said unit 55 embodying a hollow shell provided with means in its lower portion for egress of products of combustion therefrom into said lower horizontal passage opposite the opening into certain of the aforesaid passage connecting means, said shell provided also with other means for discharging ignited fuel thereinto. 60

5. A warm-air furnace embodying a casing; a furnace body housed in said casing, said body provided with horizontal upper and lower walled 65 passages, means connecting and establishing communication between said walled passages, the said passages and the said means adapted to be traversed by products of combustion, said body provided also with outer passages adapted to be 70

traversed by air being heated; and a fire-chamber unit disposed in said lower horizontal passage, the said unit embodying a hollow shell provided with egress means in its lower portion 5 for discharge of products of combustion therefrom into the lower portion of said lower horizontal passage opposite and directly towards the opening into certain of the aforesaid passage connecting means, the said shell provided also 10 with other means for discharging ignited fuel thereinto.

6. A warm-air furnace embodying a casing; a furnace body therein formed of sectional units, each said unit embodying an upper header, a 15 lower header of larger cross-sectional area than the upper header, tubular side columns connecting and establishing communication between the sides of the upper and lower headers; the lower headers together providing a horizontal heat 20 passageway extending from front to rear of said furnace body; and a fire-chamber unit embodying a closed shell and provided with means in its lower portion adapted to discharge hot products of combustion into the lower portion of said 25 heat passageway and directly towards the lower ends of said columns.

7. A warm-air furnace embodying a casing; a furnace body therein formed of sectional units, each said unit embodying upper and lower headers, the lower header having a rectangular 30 shaped lower portion and of larger cross-sectional area than the upper header, tubular side columns connecting and establishing communication between said upper and lower headers;

the said lower headers together providing a horizontal heat passageway extending from front to rear of said furnace body; and a fire-chamber unit in said heat passageway, said fire-chamber unit embodying a closed shell provided with elongated discharge means adjacent its bottom, whereby hot products of combustion are discharged from said fire-chamber unit opposite and directly towards the openings into the lower ends of said columns. 10

8. In a warm-air furnace body a horizontal heat passageway extending from front to rear thereof; spaced vertical columns opening into said passageway; and a fire-chamber unit in said passageway, said unit embodying a closed hollow shell adapted to receive hot products of combustion, said shell provided with egress openings in its lower portion through which the hot products of combustion are discharged into the lower portions of adjacent columns. 15

9. In a warm-air furnace body a horizontal heat passageway extending from front to rear thereof; spaced vertical columns opening into said passageway; and a fire-chamber unit in the front portion of said passageway and filling a major proportion of the cross-sectional area thereof, said unit embodying a closed hollow shell into which hot products of combustion are discharged, said shell provided with longitudinally disposed egress openings in its lower portion 25 through which openings the hot products of combustion are discharged into the lower portions of adjacent columns. 30

JOHN W. WESTWICK.
